United States Patent Office

Des. 208,559
Patented Sept. 12, 1967

208,559

TOY AUTOMOBILE

Jesse D. Horowitz, New York, N.Y., assignor to De Luxe
Reading Corp., a corporation of New Jersey

Filed Apr. 13, 1966, Ser. No. 1,869

Term of patent 7 years

(Cl. D34—15)

F/G. 1

FIG. 1 is a perspective view of a toy automobile, showing my new design;

FIG. 2 is a side view;

FIG. 3 is a plan view;

FIG. 4 is a front view;

FIG. 5 is a rear view; and

FIG. 6 is a bottom view.

I claim:

The ornamental design for a toy automobile, substantially as shown.
